UNITED STATES PATENT OFFICE.

ARCHIBALD E. HOPKINS AND OLIN S. FELLOWS, OF MIDDLETOWN, NEW YORK,
ASSIGNORS TO IDEAL WRAPPING MACHINE COMPANY, OF MIDDLETOWN, NEW
YORK, A CORPORATION OF NEW YORK.

KNIFE FOR CUTTING-MACHINES.

1,131,838.

Specification of Letters Patent. Patented Mar. 16, 1915.

Original application filed February 14, 1908, Serial No. 415,873. Divided and this application filed January 2, 1913. Serial No. 739,676.

To all whom it may concern:

Be it known that we, ARCHIBALD E. HOPKINS and OLIN S. FELLOWS, citizens of the United States, and residents of the city of 5 Middletown, in the county of Orange and State of New York, have invented certain new and useful Improvements in Knives for Cutting-Machines; and we hereby declare that the following is a full, clear, and exact 10 description of the same, reference being had to the accompanying drawings, and to the numbers of reference marked thereon, which form a part of this specification.

The present application constitutes a 15 division of our prior application for patent for "Automatic feeding and cutting mechanism for plastic material," filed on the 14th day of February, 1908, Serial No. 415,873, in which a rotative table is provided 20 with peripherally arranged, inwardly facing knives, against which the material to be cut was forced by suitable mechanism, although, of course, such knives may be employed in connection with machines of any 25 kind with which they are adapted for use.

The object of this invention is to afford a 30 construction which insures the utmost accuracy in setting the knives with reference to the table and the material to be operated upon.

It is also an object of the invention to afford a construction of such a nature as to 35 permit the knives after each sharpening to be almost instantaneously returned into exact adjustment without the necessity of measurements.

It is also an object of the invention to enable the knives embodying my invention to be ground until practically wholly used up.

40 It is an important object of the invention to afford a knife of such a construction and shape that when set in a circular table with the edges facing inwardly, the bevel of the blade is such with reference to the radius 45 of the table as to afford ample clearance for the cut material beyond the cutting edges of the knives, thereby preventing jamming.

It is also an object of the invention to afford a construction in which the shanks of 50 all the knives are adapted to fit closely on three sides in a suitable socket therefor to rigidly hold said knives, when adjusted from movement relative the table.

The invention embraces the matters here-

inafter described and more fully pointed out 55 and defined in the appended claims.

In the drawings: Figure 1 is a fragmentary top plan view of a circular cutting table having peripherally arranged knives embodying my invention. Fig. 2 is a perspective view of one of the knives showing the same removed from the cutting table. Fig. 3 is a section of the cutting table taken alongside of the shank of the knife to illustrate the means for engaging said knives on 60 the table. Fig. 4 is an enlarged fragmentary detail illustrating the clearance.

As shown in the drawings: 1, indicates a circular rotative cutting table, and 2 and 3, indicate kneading presser feet which act to 70 press and force the strip 4, of material to be cut against the peripherally arranged knives on said table. 5, indicates a knife set in the presser foot 3, adapted to coact with the peripherally arranged knives 7, to score 75 the strip on the inner side to facilitate the cutting. Any suitable mechanism may be employed for rotating the table and operating the presser feet and the knife 5. These form no part of my present invention, inasmuch as they are fully set forth in the other 80 application for patent hereinbefore referred to.

The periphery of the cutting table 1, is provided at uniform distances apart with 85 radial oblong seats of uniform width and depth to receive the oblong shanks 6, which fit closely thereon on three sides, and whereby each knife 7, is rigidly held in place near the periphery of the table. Said knives 7, 90 are constructed with the cutting edge in alinement with the front or inner edge of the shank, as shown in Figs. 2 and 3, and said blade of the knife is wider than said shank to permit of repeated sharpening of 95 the blade and the corresponding dressing of the front edge of the shank to maintain the alinement thereof for the cutting edge so that said knife may be sharpened and used until very little of the shank remains. 100

The bevel of the blade of the knives, as shown more fully in Fig. 4, is such with reference to the radius that said knives afford a clearance therebetween or in other words, the cutting or inner edges of said 105 knives are nearer together than the outer edges or sides of said knives. This angle may vary with the radius of the cutting

table and the distance of the knives from the center and the distance between the knives. Each of said knives is secured in place by means of a set screw 8, threaded into a suitable seat therefor in the back of each of said slots, said set screw extending inwardly and bearing against the outer side of the shank and forcing the straight inner face thereof positively against the inner vertical shoulder afforded at the inner end of said slot. Said shanks are, of course, made of sufficient length to afford a long bearing in the table and extend sufficiently below said set screw 8, as to afford a bracing construction therefor adapted to withstand great outward pressure.

The operation is as follows: When in use, a sufficient clearance is afforded between the knives to permit a free discharge of the material from therebetween, inasmuch as the rear edges of adjacent knives are farther apart than the cutting edges thereof. Inasmuch as the inner end of the slots in the table afford vertical shoulders or walls, said knives must invariably be set in the exact adjustment (if ground, with the cutting edge thereof in alinement with the inner or front edge of the shank) as shown in Figs. 2 and 3. This is of great importance, owing to the great facility it affords in setting the knives after sharpening the same and furthermore, if in grinding or sharpening the knives the shanks are at all times maintained in alinement with the cutting edge thereof, the knife may be gradually worn away by sharpening and resharpening until very little remains, or, in other words, so long as a sufficient amount of metal in the shank remains to afford a sufficient adjustment in the periphery of the table.

Owing to the fact that the set screw 8, bears against the back of the shank at the upper end thereof, and each shank fits closely in each slot in the periphery of the table with the shank bearing for its entire front or inner edge against the face of the slot, it follows that a bracing effect is afforded so that pressure on the cutting edge of each knife is transferred to the set screw which positively bears thereagainst.

Of course, the exact angle of inclination of the blade may vary with the distance of the peripherally arranged knives from the center, and therefore we do not desire to be limited to any particular angle, for obviously all that is necessary or desirable is to afford such a bevel or angle for the knife blades that the adjacent substantially flat faces of the knives shall not converge to wedge the material therebetween but shall instead preferably diverge sufficiently to afford ample clearance for the cut material, as shown in Fig. 4.

Of course, details of the construction may vary and we therefore do not purpose limiting this application for patent otherwise than necessitated by the prior art. 65

We claim as our invention:

1. A knife of the class described embracing a relatively thin stub blade, having a 70 straight cutting edge parallel throughout its entire length with both rear edges, a rectangular shank integral with the blade and having the inner face in alinement with the cutting edge of the blade, said shank being 75 narrower than the widest part of the blade.

2. A knife of the class described embracing a shank at one end shaped to fit a complementary socket on three sides, a pointless blade integral with the shank and having its cutting edge in alinement with one of the faces of the shank, said blade being of a depth to extend rearwardly beyond the shank. 80

3. A knife for the purpose specified embracing a shank at one end, having a 85 straight front face, a pointless cutting blade integral therewith and having its cutting edge in alinement with the front face of the shank, said blade being of a depth to extend rearwardly beyond the shank, and of a tapering thickness toward cutting edge such that a plurality of said knives arranged to face radially inward at a given circumference afford a distance therebetween at the rear edges greater than the distance between 90 the same at the cutting edges. 95

4. A knife comprising a rectangular shank at one end, a pointless blade wider at the top than the shank having a cutting edge in alinement with one edge of the 100 shank and said blade providing a clearance on each side between the cutting edge and back edges.

5. A knife comprising a shank at one end having parallel side faces and parallel front 105 and rear faces, a stub blade of greater width at its widest part than the shank having a cutting edge in alinement with the front face of the shank.

6. A knife for cutting machines comprising 110 a rectangular shank at one end and an integral uniformly cross-sectioned triangular blade of greater depth than the shank ground on each side beyond the rear edge of the shank to provide clearance beyond the 115 cutting edge, said blade being offset at its rear edge beyond the shank to afford greater width.

In testimony whereof we have hereunto subscribed our names in the presence of two 120 subscribing witnesses.

ARCHIBALD E. HOPKINS.

OLIN S. FELLOWS.
